CLAIM

The ornamental design for a rubber mat for avionics box, as shown and described.

DESCRIPTION

FIG. 1 is a perspective view of the rubber mat for avionics box showing our new design;

FIG. 2 is a front view of the rubber mat for avionics box of FIG. 1;

FIG. 3 is a back view of the rubber mat for avionics box of FIG. 1;

FIG. 4 is a left view of the rubber mat for avionics box of FIG. 1;

FIG. 5 is a right view of the rubber mat for avionics box of FIG. 1;

FIG. 6 is a top view of the rubber mat for avionics box of FIG. 1;

FIG. 7 is a bottom view of the rubber mat for avionics box of FIG. 1; and,

FIG. 8 is a perspective view of the rubber mat for avionics box shown in an alternate environment of use.

In FIGS. 1-8, broken lines indicate environmental structure that forms no part of the claimed design.
